Primary Examiner — Melanie H Tung(74) *Attorney, Agent, or Firm* — Sterne, Kessler, Goldstein & Fox P.L.L.C.(57) **CLAIM**

The ornamental design for an icon for a portion of a display screen, as shown and described.

DESCRIPTION

The patent file contains at least one drawing executed in color. Copies of this patent with a color drawing will be provided by the Office upon request and payment of the necessary fee.

FIG. 1 is a front view of an icon for a portion of a display screen showing my new design; and,

FIG. 2 is a front view of a second embodiment of an icon for a portion of a display screen.

The broken line showing of a portion of the display screen is for the purpose of illustrating environmental structure and forms is no part of the claimed design.
